UNITED STATES PATENT OFFICE

2,158,441

SPRING STRUCTURE FOR FURNITURE

Martin Thum, Rochester, N. Y.

Application April 1, 1938, Serial No. 199,504

4 Claims. (Cl. 155—179)

The present invention relates generally to spring structures for furniture and more particularly to spring supports of that type in which a plurality of parallel inelastic metallic straps are extended substantially across a supporting frame from front to rear, these straps being directly connected at one end to one member of the frame and having their opposite ends connected to the opposite member of the frame through elastic springs, so that the spring structure in its supporting functions operates wholly independent of the side members of the frame.

A structure of this general type is disclosed and claimed in my Patent No. 1,876,101, dated September 6, 1932, wherein upper and lower covering fabrics extending entirely over the straps and their elastic or spring connections, provide pockets in which the straps loosely extend for relative movement lengthwise as well as laterally toward and away from one another. According to this patented structure, therefore, the straps contact the upper fabric throughout their lengths, but the single thickness of this upper fabric exists between the metal straps and a cushion or load disposed on the spring structure.

It is the object of the present invention in general to retain the straps and their spring connections and at the same time substantially economize in the fabric covering, while at the same time increasing the life of the upper fabric. More particularly in this respect, it is an object of the present invention to substitute for the full lower covering fabric of my prior patent, a partial covering fabric layer in the nature of a cross web intermediate the ends of the straps, not only providing guides for the several straps, but so formed and united with the upper covering fabric as to present multi-layers of the fabric of the web between the straps and the upper fabric which will be effective to relieve the latter of undue wear in use.

It is a further object of the invention to so arrange the upper fabric that it terminates at the strap ends and is held substantially taut above the straps to further assist in preventing undue wear of the upper fabric and economize in the amount of fabric necessarily used in substantially covering the straps.

With these and other objects in mind, the invention resides in the several features to be now described in detail with reference to the accompanying drawing, forming a part of this specification, and wherein:

Figure 1 is a top plan view showing the complete spring structure.

Figure 2 is a vertical longitudinal section taken therethrough substantially on line 2—2 of Figure 1.

Figure 3 is a view similar to Figure 2 with the metallic straps and their spring connections removed.

Figure 4 is a vertical transverse section taken substantially on the line 4—4 of Figure 1, and

Figure 5 is a detail sectional perspective view showing one of the metallic straps with its spring connections and a portion of the combined upper and lower fabrics through which the strap passes.

Referring now to these figures, the spring structure of the present invention, like that of my prior patent, utilizes a plurality of parallel inelastic flat metallic straps 10, each of which may have its forward downwardly angular end 11 depending over the front rail of a rectangular frame and secured to this rail as by means of nails, tacks, or other suitable fastening members 13. 20 The rear ends of the several straps 10 are apertured as at 14 to receive the forward ends of coil springs 15, and, in the present structure, the rear ends of these springs 15 hook through U-shaped anchoring members 16 extending inwardly through bores 17 in the rear rail 18 of the frame, with their rear extensions divergently flattened against the outer surface of rail 18 to firmly hold the same for the anchoring of the rear ends of the springs 15 and consequently the rear ends of the straps 10. 25

In further accordance with the present invention, a generally rectangular section of a substantial fabric 19 extends above and along the series of straps 10, with its forward edge extending 35 downwardly over the front rail 12, to which it may be secured by nails, tacks, or like fastening members 20. The sides of the upper covering fabric 19 are turned under and stitched as at 21 to form side pockets 22 for the two side straps 10, 40 and it will be noted at this point that the entire series of straps 10 with their covering 19 are thus free to move upwardly and downwardly independent of the side rails 23 of the frame.

Along its rear edge, which terminates at the 45 rear ends of the several straps 10, the covering fabric 19 has a hem 24 and the forward hook ends of the springs 15 in their extension through the openings 14 of the several straps pierce this hem, so that the fabric 19 is in the present instance 50 drawn substantially taut across the upper surfaces of the straps 10, the several springs 15 being left uncovered.

The lower fabric is in the nature of a cross web 55 of a width substantially less than the length 55

of the upper fabric 19, having its ends extending into the side pockets 22 above described and secured by the stitching 21 which forms these pockets.

5 The web 25 has its edge portions turned upwardly and inwardly as appears at 26, and these portions 26 are fastened to the web by rows of stitching 27, which, it will be noted, pass through the material of the lower web 25 only, the stitching 27 extending parallel with the edges of the folded web and substantially spaced from said side edges. It is preferable that the folded side portions of the web 25 be also connected by rows of stitching 28 which are immediately adjacent 10 to the side edges of the web.

15 The lower web is connected to the upper covering fabric 19 by parallel rows of stitching 29, preferably arranged parallel to the side edges of the web 25 inwardly beyond the rows of stitching 20 28, and thus passing through the two folded side portions of the web as well as the upper covering fabric 19.

25 Immediately inwardly beyond the rows of stitching 29, the two thicknesses of the web 25 are pierced by slits of sufficient width to receive the straps 10, each strap being passed rearwardly through a slit adjacent to the front edge of the web and then again rearwardly through a slit adjacent to the rear edge of the web, so that a 30 portion of each strap extends between the web and the covering fabric for the major portion of the width of the web, leaving the edge portions of the web, consisting as before described of folded layers, lying between portions of the strap 35 and the upper fabric 19 from the strap receiving slits 30 of web 25 to the web edges.

40 In this way, those portions of the web lying between the straps on the upper fabric serve as cushions at spaced points, which relieve wearing contact to a considerable extent between the straps and the upper fabric.

45 It is obvious that since the straps are thus threaded through the front and rear portions of the web 25, the latter serves as a lateral guide to prevent lateral shifting of the straps to any great extent in the series, and the cushions or buffers provided by this construction between the straps and the upper fabric, coupled with the support of the upper fabric tautly across and above the 50 straps, relieve the spring structure as a whole from undue wear and not only permits of economy in the amount of fabric necessary in the first instance for the accomplishment of its purposes, but provides for substantially greater life 55 of the fabric that is necessary to be used.

What is claimed is:

1. A spring structure of the character set forth including a frame, a plurality of parallel inelastic metallic straps extending across the frame 60 and rigidly in connection at one end with one of the frame members, a series of elastic springs in connection with the opposite ends of the straps and connecting the same with the opposite frame member, a fabric overlying the said straps having an edge thereof secured to the first-mentioned 65

frame member and having its opposite edge engaged and held by the said spring members at the spring engaged ends of the straps, and a web crossing the lower surface of said fabric and secured thereto intermediate the ends of the 5 straps, said web having guide openings through which the straps extend at spaced points in the lengths of the straps, and said web having portions thereof also at spaced points in the lengths of the straps interposed between the latter and 10 the upper fabric.

2. In a spring structure including a supporting frame, a plurality of parallel inelastic metallic straps anchored at one end to a portion of said frame, and having controlling spring members in connection with the opposite ends thereof and in connection with an opposite portion of the frame, a fabric overlying the said straps and having one edge thereof securely fastened to the frame adjacent to the anchored ends of the straps 15 and having its opposite edge engaged by the said spring members adjacent to the opposite ends of the straps, and a cross web transversely of and below the straps intermediate the ends of the latter, having guide openings through which the 20 straps extend at points spaced apart in the lengths of the latter, said cross web having edge portions interposed between the straps and the upper fabric and secured to the latter.

3. In a spring structure including a supporting frame, a plurality of parallel inelastic straps securely anchored at one end to a portion of said frame, a plurality of flexible spring members engaging the opposite ends of said straps and in connection with an opposite portion of the frame, 30 an upper fabric overlying the several straps, having one edge thereof secured to the frame adjacent to the anchored ends of the straps and having the opposite edge thereof engaged by said spring members, and a guide web extending transversely beneath the straps intermediate the ends of the latter having its edge portions folded over thereon to provide a double thickness, said edge portions having openings through which the 35 straps extend at spaced points in the lengths of the latter and having portions beyond the openings interposed between the straps and the upper fabric and secured to the latter.

4. In a spring structure including a supporting frame, a plurality of parallel inelastic straps 50 anchored at one end to a portion of said frame, and a plurality of flexible spring members engaging the opposite ends of said straps and in connection with an opposite portion of the frame, an upper fabric overlying the straps having one 55 edge securely fastened to the frame adjacent to the anchored ends of the straps and having its opposite edge engaged by said spring members, and a guide web extending transversely of the several straps intermediate the ends of the latter, 60 having guide openings through which the straps extend and having portions below the straps and other portions interposed between the straps and the upper fabric and secured to the latter.
